Aaron Gould of Washington of Litchfield St of Connec-

Letters Patent

The Schedule referred to in these Letters Patent and making part of the same, containing a description in the words of the said Aaron Gould himself, of his improvement in the art of dyeing hats.

To all to whom these Presents shall come -

Be it known, that I, Aaron Gould of Washington in the County of Litchfield and State of Connecticut, have invented a new and useful improvement in the art of dyeing and coloring hats, and the following is a full and exact description thereof - I Recr.

The hats may be put loose into the liquor or dye, without blocks or the use of a wheel, or may be placed loose in a basket or crock, and set into the kettle, which may be either round oval or square and may be taken from the dye kettle in the basket or crock as occasion may require for the purpose of airing or otherwise, until the color becomes perfect, this method without the use of blocks or a wheel gives a free and even circulation to the coloring matter through every part of the hat, and produces a bright and permanent color without the risk of rubbing the fur off from the hats or exposing them to damage in various ways which the former method of using a block or blocks and wheel often did - October 19, 1835.
